UNITED STATES PATENT OFFICE

GEORGE B. BEAMAN, OF CRAFTON, PENNSYLVANIA, ASSIGNOR TO SUPERIOR PAPER PRODUCTS COMPANY, OF CARNEGIE, PENNSYLVANIA, A CORPORATION OF DELAWARE

FABRICATED PACKAGE

Application filed December 23, 1929. Serial No. 415,924.

This invention relates to packages and cartons of the type employed for packaging articles for shipment, and it has for its primary object the provision of a package in which various commodities may be dependably packed for shipment at a very low cost with a minimum amount of labor and care.

Another object is to provide a package of this character in which a systematically organized and cooperatively associated arrangement of packing and spacing members are utilized for holding the articles from shifting about in the casing employed in the package, and also for yieldably spacing them from the ends and side walls thereof in such a way as to afford them adequate protection against injury from the jars and shocks normally encountered when the package is shipped from one place to another.

A further object is to provide a package of the above described character which in addition to being of simple and inexpensive construction, although not necessarily so limited, is especially adapted for use in packaging cylindrical and disk-shaped articles.

These and other objects as well as the novel features and advantages of the invention will become more apparent when the following detailed description is read in conjunction with the accompanying drawings of which Fig. 1 is a sectional view taken vertically through a package constructed in accordance with this invention in which an elongate cylinder is encased; Fig. 2 is a horizontal sectional view looking at one end of a similarly constructed package; Fig. 3 is a plan view of a spacer member used intermediate the ends of the package; Fig. 4 is a similar view of an end spacer member; and Figs. 5, 6, 7, 8 and 9 are end views of various forms of packing members.

Having reference now to the drawings, and first to Fig. 1, the invention is illustrated as being embodied in a package in which a glass cylinder 1 of the type employed in gasoline dispensing pumps is shown packed for shipment. The package as illustrated comprises a paper board box

or casing 2 having dimensions somewhat larger but substantially approximating those of the cylinder 1. For spacing the cylinder or whatever object may be placed in the package from the end and side walls of the casing, packing members 3 are employed. These members are preferably positioned at the opposite ends of the casing with portions extending between the ends of the cylinder and the end walls of the package and other portions extending between the side walls of the cylinder and package whereby spacing the cylinder from both the end and side walls of the casing and also holding it in fixed position therein so that it will not shift about in the casing when the package is moved.

In order that the cylinder will not be broken or otherwise damaged when the package is tumbled or tossed about, the packing members are made of some suitable yieldable material capable of absorbing the deleterious forces imparted in such way to the package, thus preventing them from being transmitted to the cylinder. Packing members of this type may be made of various materials, such as corrugated paper board and the like which are particularly adapted because of their strong flexible cellular-like structure, for uses of this nature. In making these members out of corrugated paper board, the paper board is first cut in strips of correct length and width and then folded upon themselves to the desired shape, and preferably in the shapes illustrated in Figs. 5, 6, 7, 8 and 9. After being folded in the desired shape they are bound together with strips 5 of adhesive tape or other suitable binding devices.

For preventing the packing members from getting out of the place in the packing case, and for simplifying their arrangement therein, spacer members 4 of the shape shown in Fig. 4 are employed. These spacer members comprise simply plain stamped or cut blanks of paper board having notches 6 cut in their sides for the reception of the vertically disposed portions of the L-shaped packing members extending along the side walls of the casing. Hence when placed in

position they firmly hold the packing members in place and at the same time form a false or resilient inner wall for the package.

When the articles being packaged are elongate in form such as the cylinder 1, or comprise a number of disks such as phonograph records, it is desirable to include packing means intermediate the ends of the package to prevent the articles from shifting, and also protect them against injury due to the side walls collapsing when other objects are encountered. To simply reinforce the side walls, packing members 7 of the form shown in Fig. 8 may be positioned about the sides of the article in the same manner that the end packing members are arranged. For holding such members in place a spacer member 8 of the type shown in Fig. 3 is arranged in the casing in the desired position, and if necessary attached to the walls of the casing by adhesive tape or other suitable means, notches 9 being cut in the blank to engage the packing members. Packing members 7 of the form shown in Fig. 8 are also especially adapted for use in packing flat fragile articles, such as mirrors, for shipment. With such articles the packing members are placed about their edges in the manner shown in Fig. 8, and where necessary spacer members 4 may be used to hold them in place.

Another method of reinforcing the side walls of the casing and providing packing material between the walls and the articles placed in the casing is to form the packing members in the shape shown in Fig. 7. When packing members such as this are used, the elongate portion 11 definitely spaces the articles from the side walls of the casing along their entire length.

It will be appreciated by those skilled in the art that the packing members may be made in a number of different ways, and when made of cellular paper board as well as other material they may be folded in many different shapes depending on the shapes of the articles being packaged.

While the invention is illustrated here in connection with a package especially adapted for packaging cylindrical and disk-shaped articles such as phonograph records, it will be readily understood that it may be applied to various other shapes of articles.

With round articles as illustrated, the maximum protection is afforded the articles by placing the packing members midway between the opposite corners of the casing so that they will make tangential engagement with the sides of the articles. But with articles of other shapes, as will be readily appreciated, the packing members may be disposed in various other relations about the ends of the package according to

the shape of the articles to provide the same form of protection.

The chief advantage of the invention resides in the simplicity of the packing arrangement and the ease with which it may be applied to a package and the security which is afforded by it.

According to the provisions of the patent statutes, I have explained the principle and operation of my invention, and have illustrated and described what I now consider to represent its best embodiment. However, I desire to have it understood that, within the scope of the appended claims the invention may be practiced otherwise than as specifically illustrated and described.

I claim:

1. A shipping carton comprising an outer casing having end and side walls, a paper board spacer member loosely disposed within said casing, and a plurality of resilient members detachably arranged in the casing with portions extending between the end of the casing and spacer member and yieldably spacing it therefrom, and other portions extending through openings in the spacer member and along the side walls of the casing in a manner to yieldably space an article packed in the carton from the side walls of the casing, said resilient members being arranged midway of the sides of the casing and walls and maintained in position by the spacer member.

2. A shipping carton comprising an outer casing having a plurality of detachable packing pads formed of compactly folded sections of corrugated paper board arranged at spaced intervals about the walls thereof for the protection of objects packed in the carton, and a detachable spacing member arranged within said casing for holding said pads in their selected spaced relation, said spacing member having openings about its edges in which said pads are engaged.

3. A shipping carton comprising an outer casing having side and end walls, a detachable spacer member arranged to form a false end for the casing, and a plurality of L-shaped pads formed of compactly folded corrugated paper board detachably positioned at spaced intervals about the casing with one leg of each extending between said spacer member and the end of the casing and the other passing through one of a plurality of openings provided for that purpose in the spacer member and extending along the side wall of the casing, said pads being held in place by being engaged in said spacer member opening.

In testimony whereof, I sign my name.

GEORGE B. BEAMAN.
